UNITED STATES PATENT OFFICE.

JOHN CURTIN, OF MARION, VIRGINIA.

PLAITING-BOARD.

SPECIFICATION forming part of Letters Patent No. 316,012, dated April 21, 1885.

Application filed September 17, 1884. (No model.)

To all whom it may concern:

Be it known that I, JOHN CURTIN, a citizen of the United States, residing at Marion, in the county of Smyth and State of Virginia, 5 have invented a new and useful Improvement in Plaiting-Boards, of which the following is a specification, reference being had to the accompanying drawings.

My invention relates to plaiting-boards; and 10 it has for its object to provide a device of this character with a roller for keeping the cloth being operated upon smooth and prevent it from becoming wrinkled.

A further object of the invention is to provide 15 a plaiting-board with adjustable pivoted spring presser arms or rods for holding the cloth being operated upon in position.

A further object of the invention is to provide 20 a plaiting-board which shall be cheap and simple in its construction, effective in its operation, and one that will be strong and durable.

With these ends in view the invention consists in the improved construction and in the 25 combination and arrangement of the various parts, hereinafter fully described, and pointed out in the claims.

In the drawings, Figure 1 is a perspective view of a plaiting-board constructed in accordance 30 with my invention, showing both of the spring presser-arms lowered. Fig. 2 is a side elevation showing both of the arms raised. Fig. 3 is a detail view of the plaiting-knife.

In the accompanying drawings, in which 35 like letters of reference indicate corresponding parts in all the figures, A represents the board, having at its forward end, on each side thereof, a forwardly-extending arm, B. Between said arms, just in front of the board A, is journaled a roller, C, the purpose of which 40 is to keep the cloth being operated upon smooth and prevent it from becoming wrinkled when it is fed onto the face of the board. Upon the sides of the plaiting-board, near each end 45 thereof, are provided a series of holes or openings, a. Upon each side of the board, near the forward end thereof, fitted in any one of the series of holes or openings a, is a staple, b. Fitted in said staples are the ends of a presser- 50 arm, D. Said presser consists of a single piece or strip of stiff wire having its ends bent to

form hooks c, which engage said staples, and thus pivotally secure said presser-arm thereto. At the other end of the table is a presser-arm, E, which is somewhat similar in construction 55 to that already described, with the exception that it is pivoted a slight distance above the table and has a U-shaped portion, d, and also has a portion, e, which lies flat upon the board. These presser-arms are connected by a series 60 of tapes, e', which serve to hold the ends of the presser arms in engagement with the staples, and also holding the cloth flat and smooth upon the table or board.

In operation the spring presser-arm at the 65 forward end of the board is raised and the cloth passed between it and the roller. Said presser-arm is then lowered and holds the cloth in position. The presser-arm at the other end of the board is then raised, and the 70 end of the cloth passed underneath the same, after which it is lowered, and the cloth plaited by means of a knife of the construction shown in Fig. 3. The tapes may be tightened at any time by withdrawing the staples and moving 75 them to the next adjacent hole in the board.

It will be seen from the above description that a plaiting-board constructed in accordance 80 with my invention is simple, may be manufactured and supplied at a slight cost, and that its operation is thoroughly efficient and effective.

Having fully described my invention, what I 85 claim as new, and desire to secure by Letters Patent, is—

1. The combination, in a plaiting-board, with board A, of a roller journaled at one end thereof, and a spring presser-arm having its free portion resting on said roller.

2. The combination, with the board A, having a roller journaled at one end thereof, of spring presser-arms located one at each end of the board, and tapes connecting said arms, substantially as set forth.

In testimony that I claim the foregoing as 95 my own I have hereto affixed my signature in presence of two witnesses.

JOHN CURTIN.

Witnesses:

M. M. SEAVER,
JOHN M. WILSON.
